Primary Examiner — John R Yeh*Assistant Examiner* — Dustin Andrew Griffith(74) *Attorney, Agent, or Firm* — Dickinson Wright PLLC(57) **CLAIM**

The ornamental design for a basket, as shown and described.

DESCRIPTION

FIG. 1 is a perspective view of the basket of our design; FIG. 2 is a front elevation view of the basket of our design; FIG. 3 is a rear elevation view of the basket of our design; FIG. 4 is a side elevation view of the basket of our design; FIG. 5 is a side elevation view of the basket of our design, taken from the opposite side of that shown in FIG. 4; FIG. 6 is a top view of the basket of our design; and, FIG. 7 is a bottom view of the basket of our design. The dash-dash broken lines depict portions of the basket that form no part of the claimed design. The dash-dot-dot-dash line in FIGS. 6 and 7 depicts the boundaries of the claim in the top and bottom views.

1 Claim, 6 Drawing Sheets(56)
